H. C. MALLORY

ENGINE COOLING SYSTEM

Filed Oct. 30, 1922

INVENTOR
Harry C. Mallory
BY John E. Hubbard
his ATTORNEY

UNITED STATES PATENT OFFICE.

HARRY C. MALLORY, OF NEW YORK, N. Y.; SUE R. MALLORY ADMINISTRATRIX OF
SAID HARRY C. MALLORY, DECEASED.

ENGINE-COOLING SYSTEM.

Application filed October 30, 1922. Serial No. 597,789.

The general object of my present invention is to provide an improved cooling system especially adapted for use in cooling the cylinder walls of internal combustion engines of relatively large size, such as the Diesel engines employed in ship propulsion.

My improved cooling system is of the boiling and condensing type, in which all or practically all of the heat abstracted from the engine by a cooling liquid in the engine cooling space or spaces is normally utilized in vaporizing the cooling liquid and is dissipated in a condenser in which the vapor is condensed, and which system preferably comprises provisions for keeping the system sufficiently free from air so that a pressure less than that of the atmosphere may be maintained in the cooling system, and the boiling point of the cooling liquid may be correspondingly low. My invention comprises means directly responsive to the temperature or to the vapor pressure in the cooling system, for regulating the flow of the water or other condenser cooling fluid through the cooling space of the condenser which I employ to condense the vapors of the engine cooling liquid generated by the heat absorbed in the engine cooling space or spaces. Advantageously the cooling system is of such character that the liquid of condensation formed in the condensing space of the condenser is returned to the engine cooling space or spaces.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described a preferred embodiment of my invention.

The one figure of the drawing is a diagrammatic elevation with parts broken away and in section.

In the embodiment of my invention illustrated, by way of example, in the drawing, A represents an internal combustion engine, the cylinders A' of which are surrounded by a liquid containing a cooling jacket space A² with an outlet A³ at its top from which vapor may pass through the vapor pipe B to the steam inlet of a condenser C. The condenser

C, as conventionally illustrated, is a surface condenser with an intertube steam space C' traversed by tubes which open at their ends into chambers in the end heads of the condenser. One end head of the condenser is formed with two chambers C² and C³, so arranged that cooling water supplied to the chamber C², passes from the latter through approximately half of the tubes of the condenser into the chamber C⁴ at the opposite end of the condenser and returns from there through the other condenser into the chamber C³ from which it passes to waste, or a suitable storage space (not shown) through a waste pipe C⁵.

Water or other condenser cooling fluid is supplied to the chamber C' at the required rate by suitable means responsive to conditions in the engine cooling system. The means for this purpose illustrated, comprise a reciprocating steam pump D, having its water cylinder outlet connected to the chamber C², and having its steam cylinder receiving steam through a steam supply pipe E at a rate determined by the adjustment of a valve F. The latter as shown is thermostatically operated, and opens and closes as the pressure rises and falls in a pressure fluid pressure motor chamber F', one wall of which is formed by a flexible diaphragm to which the operating stem of the valve F is connected. The pressure in the chamber F' varies directly in the arrangement illustrated, with the vapor temperature in the engine cooling system. For this purpose I provide a receptacle G located in the vapor pipe B, and connected to the pressure motor chamber F' by a pipe G' leading from the bottom of the receptacle G. The chamber F' and the pipe G' are filled, and the receptacle G is partly filled by a suitable volatile liquid under such conditions that the pressure of the vapor in the receptacle will vary and thereby produce opening and closing movements of the valve F when the temperature to which the container G is subjected rises above or falls below a predetermined value.

The effect of opening and closing the valve F is to increase and decrease the rate at which the cooling liquid is forced through the tubes of the condenser C, and thereby to increase and decrease the condensing effect of the condenser. An increase in the rate at which the cooling liquid is supplied to the

condenser C by the pump D, thus tends to reduce the temperature of the vapors sweeping past the container G, while a reduction in the rate of flow of the cooling liquid through the tubes of the condenser tends to increase the temperature of the vapor. With properly designed and proportioned apparatus of the type illustrated, it is readily possible to maintain an approximately constant temperature in the vapor outlet from the engine cooling space A' regardless of the changes in operating conditions which may occur.

By suitably charging the thermostatic system comprising the container G, pipe G' and motor chamber F', the temperature which this apparatus tends to maintain in the cooling space A' may be made whatever is desired. For example, if the liquid in the thermostatic system is water, by suitably exhausting air from the system before sealing it from the atmosphere the pressure which the thermostatic mechanism tends to maintain, may readily be made 140° F., 160° F., 180° F. or any other temperature desired. The temperature which it is desirable to maintain in the cooling space of any particular engines varies with the type of engine and the conditions of use, but usually this temperature will be above 140° F., and will be appreciably below 212° F.

The water of condensation formed in the condenser and the air initially contained therein or leaking into the cooling system may be withdrawn by any usual or suitable means. As shown I withdraw both the liquid of condensation and the air by a common pump H of the wet air pump type, which discharges into a tank or reservoir I from which the water may be returned to the cooling space A' as required. As shown the reservoir I is open to the atmosphere for the escape of the air discharged by the pump H, and is provided with a water sealed liquid return pipe connection J to the engine cooling space A'. Flow from the reservoir I to the engine cooling space may be controlled by any suitable provisions, such as the conventionally illustrated float valve L, so as to maintain the desired height of liquid level in the space A'. I represents a make-up water supply connection through which engine cooling liquid may be supplied to the cooling system from time to time to make up for losses due to evaporation in the reservoir I and leakage.

Those skilled in the art will understand that with the described arrangement, the temperature in the engine cooling space can be maintained approximately constant under widely varying conditions of operation. As the engine load and the quantity of heat absorbed in the cooling space increases, the

initial temperature in the cooling system tends to increase, but any such increase in temperature acts to immediately increase the supply of steam to the pump D and hence to increase the rate at which cooling liquid is passed through the tubes of the condenser C thereby increasing the condensing capacity of the latter and restoring the normal vapor temperature in the cooling system. Conversely when the load on the engine and thereby the rate of heat absorption in the cooling space is reduced, the supply of cooling liquid to the condenser is reduced thus preventing the decreased rate of heat absorption in the cooling space from resulting in a corresponding reduction in cooling system temperature.

While in accordance with the provisions of the statutes I have illustrated and described the best forms of my present invention now known to me, it will be apparent to those skilled in the art that changes may be made in the form of my invention without departing from the spirit of my invention as set forth in the appended claims, and that certain features of my invention may sometimes be used to advantage without a corresponding use of other features.

Having now described my invention, what I claim as new and desire to secure by Letters Patent, is:

1. An engine cooling system of the boiling and condensing type comprising a cooling jacket surrounding the engines and having a vapor space at the top thereof, a condenser connected to said vapor space for condensing vapors formed by the absorption of heat by a cooling liquid contained in said jacket, means for supplying a cooling liquid to said condenser, and means for regulating the supply of said condenser cooling liquid in accordance with the temperature in said jacket.

2. An engine cooling system of the boiling and condensing type comprising a cooling jacket surrounding the engine and having a vapor space at the top thereof, a condenser connected to said vapor space for condensing vapors formed by the absorption of heat by a cooling liquid contained in said jacket, means for supplying a cooling liquid to said condenser, means for withdrawing air and liquid of condensation from said condenser, means for supplying a cooling liquid to said jacket connected to said last mentioned means, and thermostatic means for regulating the supply of said condenser cooling liquid in accordance with the temperature in said jacket.

Signed at New York, in the county of New York and State of New York, this 24th day of October, A. D. 1922.

HARRY C. MALLORY.
